United States Patent Office

Des. 193,380
Patented Aug. 14, 1962

193,380

ADVERTISING SIGN

Claude R. Kirk, 332 Moorland Road, and Samuel B.
Meadows, 2846 Montrose Ave., both of Montgomery,
Ala.

Filed Feb. 19, 1962, Ser. No. 68,870

Term of patent 14 years

(Cl. D1—12)

Fig. 1

Fig. 3

Fig. 2

Fig. 4

Fig. 6

Fig. 5

Fig. 7

FIG. 1 is a front elevational view of an advertising sign embodying our new design;

FIG. 2 is a rear elevational view thereof;

FIG. 3 is a right end elevational view thereof;

FIG. 4 is a front elevational view of a modified form of the advertising sign shown in FIG. 1;

FIG. 5 is a rear elevational view of FIG. 4;

FIG. 6 is a right end elevational view of FIG. 4; and

FIG. 7 is an enlarged sectional view taken on line 7-7 of FIG. 4.

The broken-line representation of a sign pole and let-

tering in FIGS. 1 through 6 is for purpose of illustration only.

We claim:

The ornamental design for an advertising sign, substantially as shown and described.
